(57) **CLAIM**

The ornamental design for a glove with reduced fingertip regions and a tear indicator rolled cuff, as shown and described.

DESCRIPTION

FIG. 1 is a front elevational view of an ambidextrous glove with reduced fingertip regions and a tear indicator rolled cuff in accordance with our design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a longitudinal cross-section of a middle finger region taken along line 7-7 of FIG. 2.

The broken lines illustrate environment and form no part of the claimed design.

1 Claim, 4 Drawing Sheets
